(57) **CLAIM**

The ornamental design for an stacked crystalline plate tree, as shown and described.

DESCRIPTION

FIG. 1 is a front right perspective view of a stacked crystalline plate tree showing my new design;

FIG. 2 is a rear left perspective view thereof;

FIG. 3 is a top plan view thereof;

FIG. 4 is a bottom plan view thereof;

FIG. 5 is a front elevational view thereof, the rear elevational view being identical;

FIG. 6 is a front left rotated elevational view thereof; and, FIG. 7 is a right side elevational view thereof, the left side elevational view being identical.
